UNITED STATES PATENT OFFICE.

NATHAN FRANKLIN, OF MILWAUKEE, WISCONSIN.

RADIATOR.

1,355,955.

Specification of Letters Patent.

Patented Oct. 19, 1920.

Application filed September 19, 1919. Serial No. 324,835.

To all whom it may concern:

Be it known that I, NATHAN FRANKLIN, a citizen of the United States, and resident of Milwaukee, in the county of Milwaukee and State of Wisconsin, have invented certain new and useful Improvements in Radiators; and I do hereby declare that the following is a full, clear, and exact description thereof.

10 My invention relates to new and useful improvements in radiators, more particularly of that type adapted for use in connection with the cooling systems of automobile or other power plants, and comprising pairs 15 of elongated plates extending transversely of the plane of the body of the radiator, the longitudinal edges of each pair of plates being connected together to define narrow passageways rendered tortuous in nature by 20 providing sinuous cross sections for the plates to procure a desired expanse of cooling surface between the pairs of plates.

It is in general the object of my invention to improve the construction of radiators of 25 this character, and it is more particularly my object to provide an arrangement effecting an increased expanse of radiating surface whereby to increase the cooling efficiency of the radiator. It is further my object in this connection to provide such increased radiating surface without unduly obstructing the air spaces between the passageway-forming pairs of plates whereby to permit free passage of the air through 35 the radiator, and free access to the spaces between the plates for the purpose of repair.

It is further my object to provide an arrangement wherein the sinuous cross sectional shaping of the passage plates permits 40 ready expansion and contraction of the various portions of the plates incidental to changes of temperature.

With the above and other objects and advantages in view, which will be apparent as 45 the description proceeds, my invention resides in the novel features of construction, combination and arrangement of the parts as hereinafter described and defined by the appended claim.

50 In the accompanying drawings:

Figure 1 is an elevational view of a radiator constructed in accordance with my invention.

Fig. 2 is a vertical sectional view taken 55 through a portion of the radiator mesh on a plane extending longitudinally of the

body of the radiator, as indicated by the lines 2-2 of Figs. 3 and 4.

Fig. 3 is a vertical transverse sectional view through the radiator mesh on the plane 60 indicated by the line 3-3 of Fig. 2, and

Fig. 4 is a horizontal sectional view of a portion of the radiator mesh on the plane indicated by the line 4-4 of Fig. 2.

Referring now more particularly to the 65 accompanying drawings, A and B designate respectively the upper and lower heads of a radiator structure of the automobile type embodying my invention, pairs of mating plates 5, 5 6, 6 and 7, 7, etc., extending vertically between these heads, the plates being disposed transversely of the general plane of the radiator body whereby to provide the usual air cells therebetween, the passageway defined by each pair of plates communicating in the usual manner with the radiator heads A and B. The air cells between pairs of passage forming plates are divided by flat plates 8, foraminous in nature. 70

80 My invention resides in the particular cross sectional shaping of the plates to procure an increased radiating surface thereof and to lengthen the path of travel of the water or other fluid to be cooled with respect to said radiating surface. Thus, each of the plates is provided with a series of regularly spaced bends s extending transversely therethrough and directed outwardly with respect to the passageway 75 formed between each pair of plates, the sides of these bends slightly spaced to form water chambers extending transversely of the planes of the plates, and the end portions of the bends are crimped together 85 forming resultant shoulders t which close the ends of these water chambers. The edge portions of each pair of plates are also offset toward each other for mutual engagement, forming resultant shoulders u which 90 close the sides of the main passageway formed by the pair of plates. The bends therefore define transverse hollow ribs on the walls of the passageway formed by each pair of plates and these bends or ribs form 95 100 expansion or contraction sections compensating for the changes in temperature to which the plates are subjected, as will be noted particularly by reference to Fig. 2.

The plates are also provided between each 110 pair of bends s with a pair of outwardly struck portions v extending longitudinally

2
of the bends, the outer ends of said portions *v* terminating adjacent the shoulders *u*, while the inner end of the portions are mutually adjacent and inclined in the same 5 direction whereby to define an oblique baffle portion *w* in the passageway.

In assembling the radiator structure, a series of pairs of plates are placed together and suitably held with the bends of the 10 plates in abutting relation to the plates *s*. The side edge portions of the plates in this assembled structure are then dipped in solder in the usual manner to connect the plates together and to insure sealing of the 15 passageway between the pairs of plates.

I thus provide a radiator mesh having series of air cells or interstices which are rectangular at their end portions, with their walls lying respectively parallel and at 20 right angles to the planes of the constituent plates, the intermediate portions of these air cells or interstices being reduced by the increased width of the hollow portions of the ribs or bends and by the outwardly 25 struck portions *v* of the plates. A readily constructed radiator structure is thus provided which is exceedingly efficient by reason of the increased radiating area afforded by the various cross sectional shapes of the 30 plate, and it is noted that water in passing downwardly through the passageways of the plates will flow into the bends or ribs *s* and into the outwardly struck portions *v* of the plates to most fully utilize the cooling 35 effect of all of the radiating surfaces between the shoulders *t* and *u*, it being noted that more or less of a churning action would be set up with respect to water flowing through the passageways by reason of

the various enlargements and transverse 40 branches thereof, the oblique plate portion *w* also tending to procure this result.

While I have shown and described a preferred embodiment of my invention, it will be appreciated that various changes and 45 modifications of structure may be employed to meet differing conditions of use and manufacture, without departing in any manner from the spirit of my invention.

What is claimed is:

A radiator structure comprising a series of pairs of plates, the plates of each pair having their side edge portions engaged to define a closed passageway between the plates, said plates of each pair being provided with series of transverse bends, the opposed portions of said bends being substantially parallel and spaced to provide fluid chambers opening in said passageway, the bends of each pair of plates being in 60 abutting relation to the bends of adjacent pairs of plates to provide mutual connection for said series of pairs of plates and to define air cells extending between said pairs of plates, said plates being provided between the said bends thereof with pairs of portions struck outwardly between the bends and extending longitudinally between the bends, the inner ends of each of said pairs of outwardly struck portions being 65 mutually adjacent and inclined in the same direction to define an oblique baffle portion therebetween.

In testimony that I claim the foregoing I have hereunto set my hand at Milwaukee, 75 in the county of Milwaukee and State of Wisconsin.

NATHAN FRANKLIN.
